United States Patent Office

Des. 183,470
Patented Sept. 2, 1958

183,470

REAR TRUNK LID FOR AN AUTOMOBILE

Clifford C. Voss, Clawson, and William M. Brownlie, St. Clair Shores, Mich., assignors to Chrysler Corporation, Highland Park, Mich., a corporation of Delaware

Application July 29, 1957, Serial No. 47,126

Term of patent 14 years

(Cl. D14—18)

FIG. 1

FIG. 3

Fig. 1 is a top plan view of a rear trunk lid for an automobile showing our new design; and

Figs. 2 and 3 are sectional views taken on the lines
2—2 and 3—3 of Fig. 1.

We claim:

The ornamental design for a rear trunk lid for an automobile, substantially as shown.
